Jiang, L., "Marker," U.S. Appl. No. 29/433,637, filed Oct. 2, 2012.
(Continued)*Primary Examiner* — Elizabeth Albert(74) *Attorney, Agent, or Firm* — Christensen O'Connor Johnson Kindness PLLC(57) **CLAIM**

The ornamental design for a pen cap, as shown and described.

DESCRIPTION

FIG. 1 is a bottom front perspective view of a pen cap showing my new design;

FIG. 2 is a right side elevation view thereof, with the left side elevation view being a mirror image of the right side elevation view;

FIG. 3 is a front elevation view thereof, with the rear elevation view being a mirror image of the front elevation view;

FIG. 4 is a top plan view thereof; and,

FIG. 5 is a bottom plan view thereof.
